Atty.

UNITED STATES PATENT OFFICE.

EDUARD STRAUB, OF SULGEN, SWITZERLAND.

FURNACE FOR BURNING LIQUID FUELS HAVING THE TENDENCY TO BURN WITH A STRONGLY-SOOTING FLAME.

1,313,136.

Specification of Letters Patent.

Patented Aug. 12, 1919.

Application filed November 5, 1918. Serial No. 261,244.

To all whom it may concern:

Be it known that I, EDUARD STRAUB, a citizen of the Republic of Switzerland, residing at Sulgen, Switzerland, have invented certain new and useful Improvements in Furnaces for Burning Liquid Fuels Having the Tendency to Burn with a Strongly-Sooting Flame; and I do hereby declare the following to be a clear, full, and exact description of the invention, such as will enable others skilled in the art to which it appertains to make and use the same, reference being had to the accompanying drawing, and to figures of reference marked thereon, which form a part of this specification.

This invention relates to improvements in furnaces for burning liquid fuels having the tendency to burn with a strongly soot-ing flame.

In the furnaces hitherto proposed it is only possible to burn liquid fuels so as to prevent a clogging of the air passages when provision for a supply of compressed air is made. For this reason it was not possible to use till now liquid fuels in furnaces working only with a natural air draft.

The object of the present invention is to provide a furnace for burning liquid fuels working with a natural air draft in which no soot is produced.

The furnace according to the present invention comprises a flat cup resting on legs and arranged at the beginning of a channel in which a natural air draft is produced. This cup has a front wall causing the air drawn through said channel to stream at a certain distance above the flat cup past the latter. The furnace according to this invention comprises also means for supplying liquid fuel to the front wall of the cup, which fuel vaporizes as soon as it comes in contact with the flat bottomed portion of the cup, the current of air present above this cup portion flowing in a direction forming a right angle with the vertically rising vapors of fuel. Preferably the bottom of the cup is provided with a plurality of holes.

The invention consists also in the particular construction, arrangements and combination of parts of the furnace, as will hereinafter be fully set forth and pointed out in the claims, reference being had to the accompanying drawing showing by way of

example several embodiments of the invention.

In this drawing:

Figure 1 is a vertical cross-section through a heating furnace constructed in accordance with the present invention,

Fig. 2 is a section on the line II—II of Fig. 1.

Fig. 3 is a side view of the furnace.

Fig. 4 is a section on the line IV—IV of Fig. 3, and

Fig. 5 is a view corresponding to Fig. 3 showing a modification of a detail.

Figs. 6 and 7 show another form of the front wall of the furnace, Fig. 7 being a section on the line VII—VII of Fig. 6.

Referring to the drawing, 1 denotes a muffle arranged within the heating chamber of the furnace and exposed on all sides to the heating action of the combustion gases.

The flues of the furnace comprise a channel 2 guiding the combustion gases from the combustion chamber or space 3 into the heating chamber 7. The latter communicates by means of passages 8, 8 with horizontal channels or flues 9, 9 connected at their turn with vertical channels 10, 10 communicating with horizontal channels 11, 11. The latter are connected by means of passages 12, 12 with a common flue 13 communicating with the chimney of the furnace, which chimney is not shown on the drawing.

4 denotes a pivotally mounted hood provided near the outer end of the combustion space 3 and causing the air for combustion streaming through a vertical channel 6 and a horizontal channel 5 arranged below the combustion space 3 and the horizontal channel 2 to pass into the space 3. The channel 6 communicates at its upper end with the atmosphere. As shown in Fig. 1, the channel 5 provided for the supply of fresh air is arranged near the combustion space 3 and the flue 2, so that the air passing through it is pre-heated.

The furnace proper is arranged at the beginning of the flue within the combustion chamber 3. It comprises a cup 17 (Fig. 3) resting on four legs 19 formed integral therewith; the air for combustion is adapted to come on all sides in contact with said cup. The cup 17 is very flat and it is provided in its bottom portion with a plurality of tube-like holes 20. The cup 17 comprises

further a front wall 16 projecting beyond the bottom portion of the cup. 23 denotes a supply pipe for the liquid fuel.

18 denotes an adjustable covering plate 5 having the shape of an angle iron and adapted to be placed in front of the cup when it is desired to prevent the air for combustion from coming in contact with the bottom of the cup 17.

10 14 is a plate arranged above the combustion space 3, a narrow passage 15 for the air for combustion being provided between the plate 14 and the upper end of the front wall 16 of the cup.

15 In the furnace shown in Fig. 5, the rear end of the cup 17 touches the bridge 3¹ of the flue, while in the furnace shown in Figs. 1-4 a certain space is provided between cup 17 and bridge 3¹. In the second embodiment no covering plate 18 is required.

The furnace shown in Figs. 6 and 7 comprises a cup 17 having a front wall 16 extending up to the plate 14 and provided 25 with an opening 22.

The working of the improved furnace is as follows:

When the cup 17 has been filled with a small quantity of liquid fuel, the latter is 30 ignited and the hood 4 is then closed. The air for combustion flows now in consequence of the natural air draft present within the channels 6 and 5 through the latter and passes then into the hood 4 and from the 35 latter, at a certain distance above the flat portion of the cup 17, into the combustion space 3 where it comes in contact with the vertically rising and at first strongly sooting flame of the burning fuel carrying 40 thereby with it the gases, which contain for the present still much carbon. Owing to this, a further layer of the burning fuel is caused to come in contact with the highly pre-heated air for combustion, a perfect 45 combustion of the fuel being thus attained and a very high temperature being produced beneath the muffle 1. In consequence of the fact that the air for combustion enters near the top of the chamber 3 into the latter, the 50 flame is not deflected downward by said current of air, so that a very intimate contact between the hot combustion gases and the muffle 1 is obtained. The temperature produced within the combustion space 3 has 55 the effect to heat the cup 17 gradually to such a temperature that the fuel still contained in the cup is vaporized and caused to burn. When this is the case, liquid fuel is supplied to the cup 17 through pipe 23, 60 a member controlling this supply being adjusted in such a manner, that the liquid fuel dripping on the cup 17 is immediately vaporized owing to the high temperature of the cup. The current of air caused to 65 stream in consequence of the natural air

draft present in the furnace from the hood 4 into the combustion chamber 3, crosses at right angles the fuel vapors rising from the cup 17, so that the air for combustion and said vapors are caused to mix in a very 70 intimate manner producing thereby a mixture which burns without producing any soot.

It will be seen, that in the furnaces according to the present invention the air for combustion is only able to mix with vapors of the liquid fuel and not with the liquid fuel itself, and that oxygen is supplied in such a quantity to provide for a complete combustion of said vapors, thus avoiding any 75 production of soot which is always produced only in consequence of an imperfect combustion and a too low temperature of combustion.

I claim:

1. A furnace for burning liquid fuels having the tendency to burn with a strongly sooting flame, comprising a flue with a natural air draft, a vaporizer plate arranged within said flue adapted to be heated by the 90 combustion taking place in said flue above the evaporating temperature of the liquid to be burned, the longitudinal axis of the plate extending in the direction in which the air of combustion admitted before said plate 95 into the flue has the tendency to stream through the latter, and means to sprinkle from above and at right angles to the current of the air of combustion streaming through the flue, liquid fuel in such a quantity to said vaporizer plate during normal working of the furnace that all the supplied liquid coming in contact with the heated vaporizer is vaporized at once.

2. A furnace for burning liquid fuels having the tendency to burn with a strongly sooting flame, comprising a flue with a natural air draft, a heating chamber communicating with the flue, a muffle arranged within the heating chamber, a very flat cup arranged within said flue before the heating chamber, the cup supported above the bottom of the flue being so arranged as to extend with its longitudinal axis in the direction in which the combustion air admitted 110 before the cup into the flue tends to flow through the latter, and said cup having perforations through its bottom, and a baffle wall extending transversely across the whole flue in order to direct a portion of the combustion air over the cup, means for regulating the passage of air through said perforations, and means adapted to sprinkle from above and at right angles to the current of air directed over the cup liquid fuel in such 120 a quantity to said baffle wall during normal working of the furnace, that all the supplied liquid coming in contact with the heated cup is vaporized at once.

3. A furnace for burning liquid fuels hav-

ing the tendency to burn with a strongly sooting flame, comprising a flue provided with a bridge near its beginning and having a natural air draft, a flat cup arranged with-
5 in said flue at its beginning, legs for sup-
porting the cup, the latter touching on one
side the bridge of the flue the upper edge of
which lies on the same level as the upper
surface of the flat bottom of the cup pro-
10 vided with holes, said cup having also a
front wall extending vertically beyond its
bottom, thereby causing the air for combus-
tion to flow at a distance above said bottom
past the cup, and means for supplying a liq-
15 uid fuel to said cup, the vapors of fuel rising
vertically from the cup being crossed at
right angles by the air for combustion.

4. A furnace for burning liquid fuels hav-
ing the tendency to burn with a strongly
20 sooting flame, comprising a flue provided
with a bridge near its beginning and having a natural air draft, a flat cup arranged with-

in said flue at its beginning, legs for sup-
porting the cup, the latter touching on one
side the bridge of the flue the upper edge of 25
which lies on the same level as the upper
surface of the flat bottom of the cup pro-
vided with holes, said cup having also a
front wall extending vertically beyond its
bottom, thereby causing the air for combus- 30
tion to flow at a distance above said bottom
past the cup, means for supplying from
above a liquid fuel to said cup, the vapors
of fuel rising vertically from the cup be-
ing crossed at right angles by the air for 35
combustion, channels for supplying pre-
heated fresh air to the flue, and a pivotally
mounted hood arranged in front of said flue
and directing the pre-heated fresh air from
40 said channels into the flue.

In testimony that I claim the foregoing
as my invention, I have signed my name.

EDUARD STRAUB.
